Ill., a corporation of Ohio

Application August 21, 1937, Serial No. 71,225

Term of patent 3½ years

To all whom it may concern:

Be it known that I, William Zaiser, a citizen of the United States, residing in Rockville Centre, county of Nassau, and State of New York, have invented a new, original, and ornamental Design for a Piano, of which the following is a specification, reference being had to the accompanying drawing forming a part thereof.

In the drawing:

Figure 1 is a three-quarter perspective view of the piano, showing my new design with the cover in open position.

Figure 2 is a top plan view of the piano with the cover in closed position; and

Figure 3 is a front perspective view thereof.

The dominant features of the design reside in the outlines of the piano particularly the end panels of convex cross-section and the correspondingly shaped top, as shown.

I claim:

The ornamental design for a piano substantially as shown, and described.

WILLIAM ZAISER.
